COSMETICS

Martin Bollmann, Dessau in Anhalt, Germany,
assignor to Winthrop Chemical Company, Inc.,
New York, N. Y., a corporation of New York

No Drawing. Application April 20, 1935, Serial
No. 17,540. In Germany April 21, 1934

5 Claims. (Cl. 167—91)

My present invention relates to cosmetic preparations.

One of its objects is to improve cosmetics containing water and/or an oil such as, for instance, stearate creams, cold creams, creamlike or liquid powders and similar products with respect to their capacity to be finely spread on the skin by rubbing or to be resorbed and/or with respect to their adherence.

0 In my U. S. Patent No. 1,995,663, I have described cosmetic preparations which contain magnesium or zinc salts of such aliphatic acids which have an odd number of carbon atoms viz.—heptylic acid, nonylic acid, undecylic acid, tridecylic acid, pentadecylic acid, and heptadecylic acid.

Now, I have found that a similar improvement can be attained by the use of the free aliphatic acids which contain an odd number of carbon atoms. There come in question for the invention the free saturated acids having an odd number of carbon atoms ranging from 9 to 17 C. I prefer, however, the use of undecylic acid having particularly favorable properties.

5 The acids having an odd number of carbon atoms have remarkably better properties for the purpose in question than the acids with an even number of carbon atoms, a fact which is easily ascertainable when comparing the influence of, for instance, undecylic acid on cosmetics with that of its nearest homologous compounds, viz.—capric and lauric acid. In order to obtain the desired effect on the said cosmetics, in many cases the addition of 2% of the acid having an odd number of carbon atoms, calculated on the weight of the preparation to be made, suffices.

The examples following hereafter, serve to illustrate my invention, the parts being by weight:—

Example 1.—Liquid powder

Parts

Zinc stearate	3.8
Undecylic acid	0.2
Titanium white	8
Talc	10.5
Glycerin	6

are stirred with 80 parts of distilled water. The liquid powder thus obtained, shaken before use, can be remarkably well and uniformly rubbed on the skin and is very finely retained.

Example 2.—Creamlike powder

Parts

Zinc stearate	7.6
Undecylic acid	0.4

are finely rubbed with 15 parts of glycerin and then 10 parts of distilled water are gradually added.

One obtains a creamlike powder which is excellently spread and coats very freely and uniformly. 5

Example 3.—Stearate cream

	Parts
Potash	1.8
Borax	1 10
Glycerin	85

are heated to boiling together with 160 parts of distilled water.

17 parts of stearic acid and 0.85 part of undecylic acid are introduced while stirring, into the hot solution and stirring is continued until the mixture has become cold. The cream thus obtained spreads and coats essentially better and more uniformly on the skin than a preparation containing no undecylic acid. 15 20

Example 4.—Cold cream

	Parts
White ceresine	27
Spermaceti	25 25
Stearic acid	21
Undecylic acid	1
White and purified petroleum jelly	87

are melted together and introduced while stirring, into a hot solution of 5 parts of borax, dissolved in 36 parts of distilled water. Stirring is continued until the mixture has become cold, whereby a cream is formed which is easily and very uniformly spread and excellently resorbed. 30 35

Example 5.—Lip-sticks

	Parts
Stearic acid	19
White vaseline oil	38
Ceresine	38 40
Undecylic acid	5

are melted together and cast into the usual molds. The lip-sticks thus obtained which may be colored as desired, are distinguished by their soft and firmly adhering coating. 45

In an analogous manner, other aliphatic acids having an odd number of carbon atoms may be used.

What I claim is:—

1. Cosmetic preparations of the group consisting of creams, creamlike and liquid powders, and lip-sticks containing a saturated aliphatic monocarboxylic acid with an odd number of carbon atoms of 9 C. to 17 C. 50 55

2. Cosmetic preparations of the group consisting of creams, creamlike and liquid powders, and lip-sticks containing stearic acid and a saturated aliphatic monocarboxylic acid with an odd number of carbon atoms of 9 to 17 C.

3. Cosmetic preparations of the group consisting of creams, creamlike and liquid powders, and lip-sticks containing undecylic acid.

4. Cosmetic preparations of the group consist-

ing of creams, creamlike and liquid powders, and lip-sticks containing stearic acid and undecylic acid.

5. Cosmetic preparation of the group consisting of creams, creamlike and liquid powders, and lip-sticks comprising a suspension of zinc stearate and undecylic acid.

MARTIN BOLLMANN.
